UNITED STATES PATENT OFFICE.

BENJAMIN E. D. STAFFORD AND ETHAN I. DODDS, OF PITTSBURGH, PENNSYLVANIA,
ASSIGNORS TO FLANNERY BOLT COMPANY, OF PITTSBURGH, PENNSYLVANIA.

STAY-BOLT STRUCTURE.

1,252,307.

Specification of Letters Patent. Patented Jan. 1, 1918.

Application filed March 9, 1916. Serial No. 83,146.

To all whom it may concern:

Be it known that we, BENJAMIN E. D. STAFFORD and ETHAN I. DODDS, citizens of the United States, and residents of Pittsburgh, in the county of Allegheny and State of Pennsylvania, have invented certain new and useful Improvements in Stay-Bolt Structures; and we do hereby declare the following to be a full, clear, and exact description of the invention, such as will enable others skilled in the art to which it appertains to make and use the same.

This invention relates to improvements in stay bolt structures, and more particularly to means for testing the integrity of the stay bolts of boilers,—the object of the invention being to provide simple and efficient means which shall be readily operable to test the stay bolt without removing the cap of the stay bolt structure.

With this and other objects in view, the invention consists in certain novel features of construction and combinations of parts as hereinafter set forth and pointed out in the claims.

In the accompanying drawings; Figure 1 is a view partly in section and partly in elevation showing one embodiment of our invention; Fig. 2 is a partial sectional view taken at right angles to Fig. 1; Fig. 3 is a fragmentary view illustrating a modification of the construction shown in Figs. 1 and 2, and Figs. 4, 5, 6, 7, 8, 9, 10, 11, 12, 13, 14, 15, 16 and 17 are views illustrating various other modifications.

1 represents an outer boiler sheet having a hole for the accommodation of a bearing sleeve 2, said sleeve being exteriorly threaded at 3 to screw into the hole in the boiler sheet and said sleeve being also threaded exteriorly for the accommodation of an internally threaded portion of a cap 4. The sleeve 2 is formed interiorly with a seat 5 for the rounded or spherical head 6 of a stay bolt 7, and the inner portion of the bore of said sleeve is made tapering as at 8 to permit lateral movement of the stay bolt. The outer end of the sleeve may be beveled to form an inverted V-shaped rib 9, and the cap 4—which is annular in form having an opening 10—is made with an internal annular shoulder 11 disposed opposite the rib 9 on the end of the sleeve.

In the embodiment of our invention showing in Fig. 1, a driving member 12 is dis-

posed within the annular cap 4 and is capable of being turned therein. This driving member 12 may have a general convex form so that ample space may be provided to accommodate longitudinal movement of the bolt, and is provided with a peripheral flange 13 disposed between the rib 9 on the sleeve and shoulder 11 on the cap and engaged by both so as to effect a water-tight joint and thus guard against leakage. The member 12 is provided with a tongue 14 to enter the driving slot 15 in the bolt head. The tongue may be elongated in form and integral with the body of the member 12, and it is of such dimensions relatively to those of the slot in the bolt head as not to interfere with the longitudinal and lateral movements of the stay bolt. Instead of making the tongue 14 integral with the body of the member 12 as shown in Figs. 1 and 2, said tongue may be made separate and inserted into said member 12 as indicated at 14 Fig. 3.

The driving member 12 is made with an angular head 16 projecting outwardly through the central opening 10 of the annular cap 4, and forms, in effect a polygonal projection to be engaged by a suitable wrench. The cap 4 may also be formed with exterior faces 17 for the accommodation of a suitable wrench.

The purpose of our invention is to provide means whereby a turning force may be applied to a stay bolt without removing the cap, so that it may be at once determined whether or not the bolt is broken. Under normal conditions, the cap will be screwed tightly against the peripheral flange 13 of the driving member 12, and when the bolt is to be tested, this cap should first be loosened somewhat. The operator will then apply a suitable wrench to the head 16 of the driving member and apply a force tending to turn said driving member. Should the said driving member refuse to turn, this fact will indicate the bolt is whole, but should said member turn when rotary force is applied thereto, this fact will at once indicate that the bolt is broken.

In the form of our invention shown in Fig. 4 the rotary or driving member is indicated at 12 and is formed with a beveled or conical portion 18 seated against the beveled wall of an opening 19 in the cap 4 and with an annular lip or flange 20 to bear against

the inner face of the cap. The rotary or driving member 12^a is provided with a tongue 14^b to engage the bolt head and is made with an outwardly projecting threaded portion 21 to receive a jam nut 22, whereby the portions 18 and 20 are held tightly against their seats to guard against leakage. An angular head 23 is formed on the outer end of the rotary or driving member 12^a for the reception of a suitable wrench. By loosening the annular jam nut 22 and applying rotary force to the member 12^a, the integrity of the bolt may be tested as previously explained.

In the embodiment of the invention shown in Fig. 6, the cap is located inside instead of outside of the bearing sleeve. Thus in the construction shown in Fig. 6, the bearing sleeve 3^a is threaded interiorly for the accommodation of the annular cap 4^a, and this cap is provided with a beveled face to form a seat for the beveled portion of the rotary or driving member 12^b. The member 12^b is made with a threaded portion 21^a terminating within the upper portion of the bearing sleeve, and on this threaded portion 21^a, a jam nut 22^a is located. The threaded extension 21^a is made with an angular socket 24 to receive a suitable tool for turning the rotary or driving member 12^b to test the stay bolt, as previously explained.

In the embodiment of the invention shown in Figs. 7 and 8, the rotary driving member of the stay bolt structure, indicated at 25 is mounted to turn on the end of the bearing sleeve 3 and is normally clamped to the latter by means of a flanged ring or cap 26. The rotary driving member 25 is provided centrally with an angular enlargement 27 to receive a wrench, and said enlargement is formed with a recess or pocket 28 to receive one end of a tongue 29, the other end of the latter entering the driving slot in the bolt head. Both ends of the tongue 29 may be made wedge-shaped as shown in Fig. 7 and the dimensions of the same are such that the movements of the bolt head during normal conditions will not be interfered with.

The construction shown in Figs. 9 and 10 is similar to that shown in Figs. 7 and 8, the difference being that the rotary member 30 is made angular to receive a wrench, instead of being made hemispherical and provided with an angular enlargement as shown in Figs. 7 and 8.

In the form of the invention shown in Fig. 11, the cap 31 is made with a central enlargement 32 having an opening therein formed with curved walls to provide a partly spherical seat 33 for the spherical body of the rotary or driving member 34, the latter having a tongue 35 to enter the driving slot of the bolt head and also having an angular portion 36 to receive a wrench.

Fig. 12 shows a construction similar to

that shown in Fig. 11, except that in Fig. 12, the cap is made in two parts 31^a 31^b screwed together.

In Fig. 13, a hemispherical cap 37 is shown, and this is provided with an opening 38 for the accommodation of the rotary or driving member 39, the latter being formed with a convex portion 40 bearing against the inner face of the cap and with a threaded portion 41 to receive a nut 42 having a concave face to rest against the outer convex face of the cap. The outwardly projecting portion 41 may be provided with a slot 43 to receive a screw driver.

The construction shown in Fig. 14 embodies a cap 44 having an angular exterior with a flat outer face and a nut 45 on the rotary or driving member 46 rests against said flat outer face of the cap.

In the construction shown in Fig. 15, the cap 4 is made with a comparatively large central opening closed by a rotary or driving member 47 having a beveled portion 48 bearing against the inner face of the cap and provided with a tongue 49 to engage the slot 90 of the bolt head. A ring or washer 50 encircles the neck portion of the member 47 and rests against the cap 4. The member 47 is provided with bendable lugs 51 which are made to engage the ring 50, and thus said member is coupled to the cap 46. A central enlargement 52 is provided on the rotary or driving member 47 to receive a tool for turning the same.

In the form of the invention shown in Figs. 16 and 17, the rotary driving member is made with a head 53 having a shoulder 54, and a driver slot 55. A split ring 56 is disposed between the shoulder 54 of the head 53 and the cap 57.

Various other changes might be made in the details of construction of our invention without departing from the spirit thereof or limiting its scope and hence we do not wish to restrict ourselves to the precise details herein set forth, except as defined by the scope of the appended claims.

Having fully described our invention what we claim as new and desire to secure by Letters-Patent, is:

1. In a stay bolt structure, the combination with a stay bolt, of a testing member engaging the head of the bolt and means for swiveling said testing member whereby it is mounted to be turned without dismembering the structure, to test the integrity of the bolt.

2. A stay bolt structure, comprising a stay bolt, a bearing member, a cap, and a testing member mounted to turn and forming part of said structure, said testing member having removable connection with the bolt and being accessible for operation without dismembering the structure.

3. A stay bolt structure comprising a stay

6 bolt, a cap and a testing member, means
for swiveling said testing member between
the cap and the end of the bolt, said testing
member adapted to engage the latter for ap-
plying a turning force thereto to test the
integrity of the bolt, and means whereby
a turning force may be applied to said test-
ing member.

10 4. A stay bolt structure comprising a stay
bolt having a head, a bearing member for
said head, a cap, and a rotary member held
in place in the cap to engage the head of the
bolt for testing the integrity of the
latter.

15 5. In a stay bolt structure, the combina-
tion of a bolt and a testing member, one
of said parts having a projection and the
other part having a recess to receive said
projection whereby turning force may be
20 applied to the bolt, and means for support-
ing said testing member.

25 6. A stay bolt structure comprising a stay
bolt, a cap, and a rotary testing member held
in place by the cap to engage the end of the
bolt, said rotary testing member having a
part adapted for the reception of a tool for
30 applying rotary force to said member to
test the integrity of the bolt.

35 7. In a stay bolt structure, the combina-
tion with a stay bolt, and a cap, of means
held in place by the cap and rotative inde-
pendently thereof, said means adapted to en-
gage the end of the bolt for applying a
turning force thereto to test its integrity.

40 8. In a stay bolt structure, the combina-
tion with a bearing member, a stay bolt

having a head mounted in said bearing mem-
ber, a cap on the bearing member, and a
manually operable testing member having
a part disposed between the bearing member 40
and said cap, said testing member having
a part to engage the end of the bolt for ap-
plying turning force to the bolt for test-
ing it.

45 9. In a stay bolt structure, the combina-
tion with a stay bolt having a head, a bear-
ing member for the head of the bolt, and
a cap engaging said bearing member, of a
rotary member to engage said cap and the
head of the bolt for applying rotary force 50
to the bolt without removing the cap for
testing the integrity of the bolt.

55 10. In a stay bolt structure, the combina-
tion with a bearing sleeve, a stay bolt hav-
ing a slotted head mounted in said sleeve,
and a cap screwed on said bearing sleeve,
of a rotary member for testing the integrity
60 of the bolt and having a part disposed be-
tween the cap and the end of the bearing
sleeve and engaged by both, said rotary
member provided with a tongue entering
the slot in the bolt head, and said rotary
member also having a tool receiving part
projecting through said cap.

65 In testimony whereof, we have signed this
specification in the presence of two subscrib-
ing witnesses.
